SAMUEL TROOD, OF WILKINSBURG, PENNSYLVANIA, ASSIGNOR TO WESTINGHOUSE ELECTRIC AND MANUFACTURING COMPANY, A CORPORATION OF PENNSYLVANIA.

METHOD OF MAKING ELECTRICAL APPARATUS.

1,150,081.

Specification of Letters Patent. Patented Aug. 17, 1915.

Application filed January 7, 1914. Serial No. 810,776.

To all whom it may concern:

Be it known that I, SAMUEL TROOD, a citizen of the United States, and a resident of Wilkinsburg, in the county of Allegheny and State of Pennsylvania, have invented a new and useful Improvement in Methods of Making Electrical Apparatus, of which the following is a specification.

My invention relates to methods of making electrical apparatus, and it has special reference to electric heating devices.

The object of my invention is to provide a method of making devices of the above-indicated class which shall be simple and inexpensive and which shall secure new and highly desirable features in the completed apparatus.

More specifically, the object of my invention is to provide a method whereby, when an incasing member is cast around a conductor, the conductor will contract at the same rate as the incasing member during cooling thereof, and thus the mutual thermal contact of the parts will remain as intimate as at first, and no undue stresses will occur.

Heretofore, in devices of the general class in question, the electrical conductor has not been adapted to contact with the cooling incasing member and, consequently, undue strains have been caused, and various parts have undergone cracking or other weakening conditions, which also militated against the maintenance of intimate thermal contact between the parts.

According to my invention I embed a suitable electrical conductor or heating element in a relatively plastic cement or other suitable material of good heat-conducting and electrically insulating properties, I then preferably bake the cement, and next use the combined body as a core around which a copper or other suitable metallic incasing member is cast. Prior to and during the casting operation, I pass through the conductor a current of such value that it is caused to expand an amount that corresponds to the expansion present in the initially solidified incasing member. As the member cools and contracts, the current through the inclosed conductor is either cut off or is gradually reduced in accordance

with the temperature reduction of the incasing member, as hereinafter described. In this manner, the conductor, the inclosing material and the incasing member all cool 55 and contract at substantially the same rate, thereby maintaining intimate mutual thermal contact between the parts, while obviating the above-mentioned difficulties of cracking and the like.

In the accompanying drawing, the single figure is a view, partially in longitudinal section, and partially diagrammatic, illustrating the method constituting my invention.

Referring to the drawing, the apparatus here shown comprises an electrical conductor or heating element 1 which is preferably wound on an insulating spool 1^a; an envelop 2 therefor of relatively plastic cement 70 or other suitable material of good heat-conducting and electrically-insulating properties; an incasing member 3 of copper or other suitable metallic material, here shown as a soldering iron tip; a suitable mold 4 75 for casting the incasing member 3 around the envelop 2; supply conductors 5 for connecting the heating element 1 to a source of electrical energy (not shown); a switch 6, and a rheostat 7 for varying the current 80 supplied to the element 1.

Considering now the various steps of my process, the electrical conductor 1 and its spool 1^a are first embedded in the relatively plastic cement 2, which is fashioned in the 35 desired shape and size. The combined body is then baked, as is customary in the production of cores in the molding art, and the combined body is employed as a core for a casting of copper or other suitable material. 90 The core may be held in position during the casting process in any suitable manner, such as by the threaded collar device 8 shown in the drawing.

A predetermined time prior to the casting 95 process, the switch 6 is closed to send a current through the heating element 1 and the rheostat 7, of such value that the element is heated and caused to expand an amount corresponding to the expansion present in 100 the initially solidified tip 3. An intimate thermal contact thus obtains between the

element 1 and the tip 3. As the tip cools and contracts the current is preferably cut off immediately after solidification, if the conductor and the cast member are of the same material, and the rheostat is preferably actuated to gradually include more resistance in the circuit if the two members are of dissimilar materials, thereby, in the latter case, reducing the current traversing the heating element in such ratio that the change of temperature of the element and its contraction correspond to the temperature variation and shrinkage of the tip 3. Thus it will be noted that in either case, the tip, the cement and the heating element all cool and contract together at substantially the same rate, thereby permanently maintaining intimate thermal contact between the parts.

20 I do not wish to be restricted to the specific arrangement of parts and the structural details herein set forth, as modifications thereof may be made within the spirit and scope of my invention. I, therefore, desire that only such limitations shall be imposed as are indicated in the appended claims.

I claim as my invention:

1. The method of making an electrical device that comprises applying an electric current to a conductor during the casting of material around said conductor and thereafter cooling the said conductor and the said cast material in such manner that they contract at substantially the same rate.

2. The method of making an electrical device that comprises applying an electric current to an insulated conductor during the disposal of heated material around said conductor, and thereafter cooling the said conductor and the said material in such manner that they contract at substantially the same rate.

3. The method of making an electrical device that comprises the application of an electric current to a conductor provided with insulating material during the casting of an incasing member around said material and during a predetermined period of cooling after completion of the casting operation.

4. The method of making an electrical device that comprises the application of an electric current to a conductor during the casting of material around said conductor, and the variation of said current while said material is cooling.

5. The method of making an electrical device that comprises the application of an electric current to a conductor provided with insulating material during the casting of an incasing member around said material, and a reduction of the current in accordance with the temperature reduction of said member as it cools.

6. The method of making an electrical de-

vice that comprises applying an electric current to a conductor during the disposal of metallic material around said conductor and in good thermal contact therewith, and thereafter cooling the said conductor and the said material in such manner that they contract at substantially the same rate.

7. The method of making an electrical device that consists in disposing heated material around a conductor simultaneously passing an electric current therethrough, and thereafter cooling the said conductor and the said material in such manner that they contract at substantially the same rate.

8. The method of making an electrical device that consists in disposing molten material around an insulated conductor simultaneously passing an electric current therethrough, and thereafter cooling the said conductor and the said material in such manner that they contract at substantially the same rate.

9. The method of making an electrical device that consists in casting an incasing member around a conductor, simultaneously passing an electric current therethrough, and varying the current as the member cools.

10. The method of making an electrical device that consists in casting an incasing member around a conductor and in good thermal contact therewith, simultaneously passing an electric current through said conductor, and reducing the current in accordance with the temperature reduction of said member as it cools.

11. The method of making an electrical device that consists in embedding a conductor in insulating material, casting an incasing member around said material, supplying an electric current to the conductor during the casting operation, and varying the current as said member cools to cause the conductor to contract at substantially the same rate as the incasing member.

12. The method of making an electrical device that consists in surrounding a conductor with relatively plastic material of good heat-conducting properties, baking said material, casting an incasing member around the combined body as a core, supplying an electric current to said conductor during the casting operation and gradually reducing the current value as the member cools, whereby said conductor, material and member contract at substantially the same rate and remain in mutual intimate thermal relation.

13. The method of making an electrical device that comprises heating an electric conductor, surrounding the said conductor with heated material, and causing the said conductor and the said material to cool simultaneously and to contract at substantially the same rate.

14. The method of making an electrical de-

device that comprises surrounding with heated material a conductor that has been heated sufficiently to expand it to substantially the same degree as the said material, 5 and causing the said conductor and the said material to cool simultaneously and to contract at substantially the same rate.

In testimony whereof, I have hereunto subscribed my name this 27th day of Dec. 1913.

SAMUEL TROOD.
